UNITED STATES PATENT OFFICE.

NICOLAS GHERASSIMOFF, OF ST. GERMAIN EN LAYE, FRANCE.

PROGRESSIVE AND REVERSIBLE CHANGE-SPEED MECHANISM.

1,381,866.

Specification of Letters Patent. Patented June 14, 1921.

Application filed December 9, 1920. Serial No. 429,507.

To all whom it may concern:

Be it known that I, NICOLAS GHERASSIMOFF, a citizen of the Republic of Russia, residing at 7 Cité Médicis, St. Germain en Laye, Seine and Oise, France, have invented new and useful Improvements in Progressive and Reversible Change-Speed Mechanism, of which the following is a specification.

The present invention relates to a device for transmitting motion, which, though more especially intended for automobiles, is nevertheless capable of being utilized with the same advantages for motor-boats, machine-tools and other purposes where it is necessary either to vary the speed of a driven member or to reverse the direction of running.

The mechanism according to the present invention is of the type comprising a friction-cone with which coöperate rollers which can be moved at the will of the operator.

It presents this first novel characteristic that the shafts carrying the rollers can be made to bear more or less heavily against the cone in proportion to the effort to be transmitted. In other words, the greater the force to be transmitted the greater is the effort exerted to hold the roller in engagement with the cone, this operation being realized automatically.

It also presents a further essential characteristic consisting in a device which, by means of a lever operable by one hand, permits of first of all uncoupling the rollers, that is to say, of moving them away from the cone and consequently uncoupling the mechanism, then of moving them with a view to effecting a change of speed, after which the same lever reestablishes contact of the rollers with the cone, so as to couple up again once the desired speed is obtained. By means of this arrangement it is possible to do away with the usual clutch with its actuating pedal.

This mechanism is also characterized by the use of an additional cone, concentric to the first and also driven by the same rollers, which enables reversal of running and running backward to be obtained by the use of the same single operating lever.

It also comprises a system of direct drive.

Finally, this transmission mechanism is characterized by a special arrangement of the various parts entering into its composition.

The diagrammatic drawings annexed here-

to show, but by way of a purely indicative and in no way limitative example, a transmission mechanism constructed according to the invention.

Figure 1 is a plan partly in section. Fig. 2 is a side view and

Fig. 3 is a plan view.

Figs. 4, 5, 6 and 7, to a larger scale, are detailed views of the direct drive device.

a designates the motor shaft which is supposed, by way of example, to be that of a motor car, *b* is the driven shaft situated in the prolongation of the shaft *a* and capable of being mounted in this latter by means of a socket *b'*, or in any other suitable manner. The shaft *a* carries a driving pinion *a'*. On the driven shaft *b* is fixed a cone *c* of any suitable length and taper, according to the conditions to be fulfilled by the transmission mechanism. Parallel to the generatrices of the cone *c* are arranged two square shafts *d*, *e*, the lower extremity of which is cylindrical and is mounted in knuckle-joint bearings *d'*, *e'*, and carry pinions *d²*, *e²* engaging with the pinions *a'*. At their upper end the shafts *d*, *e* are mounted in bearings *d³*, *e³* which are subject to the action of springs *d⁴*, *e⁴* whose pressure can be regulated by means of screws *d⁵*, *e⁵*. The bearings are mounted in sleeves *d⁶*, *e⁶* suitably fixed to the frame. Contact pieces *d⁷*, *e⁷* are fixed to the bearings *d³*, *e³* for a purpose to be indicated below.

Upon the shafts *d*, *e* are mounted rollers *f*, *f'* which are arranged in such a manner that they can slide upon these shafts while being driven by these latter; with this end in view the shafts may be prismatic. These rollers are engaged by the fork *f²* of a lever *f³*, *f⁴* which, pivoting about an axis *f⁵*, *f⁶* passes through a slot *f⁷*, *f⁸* formed in a bar *f⁹* which can slide in a plane parallel to the axis of the driving and driven shafts in the standards *f¹⁰*, *f¹¹* of the frame.

The horizontal bar *f⁹* has an arm *f¹²* a portion of which is formed as a rack *g* with which meshes a wheel *g'* rotating about a shaft *g²* fixed to the frame. A pawl *g³* mounted under the pressure of a spring at a fixed point of the frame engages the wheel *g'* in such a manner that it tends to remain normally in engagement with the wheel as shown in the drawings.

At a suitable point of the frame there is arranged a shaft *h* upon which there can rotate a double arm *h'*, one end of which is given the form of a cam *h²*, while the other

extremity constitutes a support h^3 which is intended to receive an operating lever i pivoting upon a shaft i' and carrying a toothed segment i^2 which can engage in the wheel g' 5 as will be seen below.

The cam h^2 bears upon an abutment plate h^4 arranged so that it can slide in the frame and resting upon the extremities of two inclined arms j, j' . These arms, pivoting about 10 fixed axis j^2, j^3 , terminate at their lower extremities in cams j^4, j^5 which bear against the contact pieces d^4, e^4 .

Concentrically with the cone c and above this latter is arranged a cone of small length 15 h , which is used for reverse drive. This cone, the generatrices of which are in the prolongation of those of the cone c , so as to be able to be driven from the rollers f, f' , comprises an inner toothed crown h' in which two 20 pinions k^2, k^3 engage, these two latter meshing with the pinion k^4 keyed upon the driven shaft b . The pinions k^2, k^3 are mounted upon axes k^5, k^6 fixed to a cross beam k^7 or in any other suitable manner.

25 The extremity of the motor shaft a terminates in a hub a^3 , Fig. 4, in which the end of the driven shaft b is rotatively mounted and in which are formed longitudinal grooves a^4 , Fig. 4, this latter figure being a 30 section along the lines 5—5 Figs. 1 and 2. The shaft a also comprises a collar a^5 upon which there rests freely a plate constituted by a certain number of segments a^6, a^7, a^8 shown in plan in Fig. 5, these plates having 35 a central hole in which are formed projections a^9 of a form corresponding to the grooves a^4 in the hub a^3 . Above the upper face of these segments a^6, a^7, a^8 extend pins a^{10} of any suitable number intended to enter 40 recesses c' formed in the lower face of the cone c , Fig. 6, this latter figure being an end view of the cone. In these recesses are placed springs c^2 , the purpose of which is to force the projections a^9 outwardly so as to 45 move the segments a^6, a^7, a^8 away from the center of the driven shaft b .

The method of operation is as follows: Supposing the parts in the positions indicated in the drawings, the driving shaft a 50 transmits, by means of the train of gears a', d^2, e^2 , rotary movement to the shafts d, e and consequently to the friction rollers f, f' . The shafts d, e , being forced toward the cone c by the springs c^4, d^4 , this latter is 55 caused to rotate at a speed corresponding to the ratios of the elements of the train of gears a', d^2, e^2 as well as to the ratios of the diameters of the rollers and of the cone. The 60 bar f^9 , through the slots f^7, f^8 , in which pass the levers f^3, f^4 , is held in position owing to the fact that the wheel g' meshing with the rack g is locked by the pawl g^3 .

If it is desired to change the speed, the operating lever i is caused to swing from 65 right to left, Fig. 1, the effect of which is to

turn the double arm h' about its axis h and to cause the segment i^2 to mesh with the wheel g' . At the same time, the pawl g^3 has been disengaged so as to make way for the segment; the cam h^2 has pushed down 70 the bearing plate h^4 and, having caused the arms j, j' to swing toward the center of the apparatus, the cams j^4, j^5 , formed at their extremities, have pushed back the contact pieces d^4, e^4 against the action of the springs 75 d^4, e^4 , the effect of which is to move the shafts d, e and consequently the rollers f, f' from the cone c . The motion of the shaft a then ceases to be transmitted to the driven shaft e . In other words the transmission 80 system is uncoupled.

Change of speed is effected while the mechanism is uncoupled in the above manner by operating the lever i , that is to say by causing it to pivot either in one direction or the other about its axis i' , the effect of which, owing to the segment i^2 and the wheel g' is to impart a corresponding movement to the rack g which in turn moves the arm f^{12} , the bar f^9 and the levers f^3 and f^4 , which results 90 in a movement of the rollers f, f' in one direction or the other, so that these latter move toward or away from the large end of the cone.

Once this operation is finished, coupling is 95 effected again and in all cases by means of the same lever i and the same effects are reproduced but in the opposite direction, that is to say, the lever is caused to swing from left to right in order to bring it back 100 to its original position, the effect of which is to permit the arm j, j' , under the action of the springs d^4, e^4 , to resume their former position and to raise the abutment plate h^4 . The pawl g^3 reenters into engagement with 105 the wheel g' . The rollers f, f' bear again against the cone c and motion is again transmitted, but this time at a different velocity. The maneuver is therefore realized with the help of a single lever which uncouples, 110 changes speed, and couples again.

By acting lightly upon the operating lever a certain change of velocity can be obtained by merely causing the rollers to slide upon the cone. This lever could moreover be bent 115 in a desired direction so as to facilitate its operation.

If it is desired to change the direction of running of the transmission mechanism, the single lever i is operated until the rollers 120 f, f' leave the main cone c and come into contact with the auxiliary cone k . The movement given to this latter is then transmitted in the opposite direction to the driven shaft b by the intermediary of the train of 125 gears k^2, k^3, k^4 , as will be easily understood. A ball bearing may be interposed between the two cones.

If, on the other hand, it is desired to engage the direct drive, the rolls f, f' are 130

caused to slide on their shafts d , e until they leave the square portion and reach the cylindrical portion of these shafts, the effect of which is to bring these rollers into contact 5 with two of the segments a^6 , a^7 , a^8 and to move these latter toward the axis of the driven shaft b . The projections a^9 of these segments then penetrate into the grooves a^4 of the hub a^3 of the motor shaft a and, as 10 the segments are coupled to the cone c , the result is that motion is transmitted directly from the shaft a to the shaft b , without passing through the change speed mechanism, the rollers then turning idly upon their 15 shafts.

The important advantage should be pointed out that, according as the effort to be transmitted is great, the contact of the rollers with the cone is also more energetic. 20 In other words, the action of the springs d^4 , e^4 , is more strongly felt when the rollers are near the small end of the cone and when in consequence the speed transmitted is great.

Finally, it should also be pointed out that 25 the invention is not strictly limited to the diagrammatic construction, which has only been described above by way of an example; and that the arrangement of the parts could be varied to a great extent without changing 30 any of the essential characteristics of the system.

I claim:

1. A transmission mechanism comprising in combination a driving shaft, a driven 35 shaft, a cone on said driven shaft, means actuated by said driving shaft to rotate said cone, and means actuated by said cone-rotating means to couple said driving and driven shafts directly to each other.

40 2. A transmission mechanism comprising in combination a driving shaft, a driven shaft, a cone on said driven shaft, friction rollers in contact with said cone, means for driving said rollers from said driving shaft 45 and a single means for varying the point of contact of the rollers with the cone and for moving the rollers out of contact with said cone.

3. A transmission mechanism comprising 50 in combination a driving shaft, a driven shaft, a cone on said driven shaft, friction-rollers driven from said driving shaft and in contact with said cone, a second cone located adjacent said first cone, said second 55 cone having an internal gear, transmitting gear between said internal gear and the driven shaft to reverse the direction of rotation of the latter and means for moving said rollers from contact with the first cone into 60 contact with the reversing cone.

4. A transmission mechanism comprising 65 in combination a driving shaft, a driven shaft, a cone on said driven shaft, friction rollers in contact with said cone, means for driving said rollers from said driving shaft,

means for coupling said driving and driven shafts directly and means for moving said rollers out of engagement with the cone to throw said coupling into engagement to couple said shafts directly. 70

5. A transmission mechanism comprising in combination a driving shaft, a driven shaft, a cone on said driven shaft, friction rollers driven from said driving shaft and in contact with said cone, a second cone 75 located adjacent said first cone, said second cone having an internal gear, transmitting gear between said internal gear and the driven shaft to reverse the direction of rotation of the latter, means for coupling said 80 driving and driven shafts directly together, and means for moving said rollers into engagement with either cone or to actuate said coupling means as desired.

6. A transmission mechanism comprising 85 a driving shaft, a driven shaft, a cone on said driven shaft, roller-carrying shafts driven by said driving shaft, friction rollers mounted on said shafts, said shafts being mounted at one end in knuckle-bearings, 90 spring actuated means forcing the opposite ends of said shafts toward the cone, and a single lever adapted to move said shafts away from said cone and to move said rollers axially along said shafts. 95

7. A transmission mechanism comprising a driving shaft, a driven shaft, a cone on said driven shaft, roller-carrying shafts driven by said driving shafts, friction-rollers mounted on said shafts, said shafts being mounted at one end in knuckle-bearings, 100 spring actuated means forcing the opposite ends of the shafts toward the cone, a frame carrying the axes of said rollers and a single lever adapted to move said frame parallel 105 to the longitudinal axis of the cone and to move said shafts away from said cone.

8. A transmission mechanism comprising a driving shaft, a driven shaft, a cone on said driven shaft, roller-carrying shafts 110 driven by said driving shaft, friction rollers mounted on said shafts, said shafts being mounted at one end in knuckle-bearings, spring actuated means forcing the opposite ends of the shafts toward the cone, a frame carrying the axes of said rollers, a rack on 115 said frame, a gear-wheel engaging said rack, a segment engaging said gear wheel and a single lever adapted to actuate said segment and to force said shafts away from said cone. 120

9. A transmission mechanism comprising a driving shaft, a driven shaft, a cone on said driven shaft, roller-carrying shafts driven by said driving shaft, friction-rollers mounted on said shafts, said shafts being 125 mounted at one end in knuckle-bearings, spring-actuated means forcing the opposite ends of the shafts toward the cone, a frame carrying the axes of the said rollers, a rack on said frame, a gear-wheel engaging said 130

rack, a segment engaging said gear-wheel, a single lever adapted to actuate said segment and to force said shafts away from said cone and a pawl adapted to lock and unlock said gear-wheel in accordance with the movement of the lever.

10. A transmission mechanism comprising a driving-shaft, a driven shaft, a cone on said driven shaft, roller-carrying shafts driven by said driving shaft, friction rollers mounted on said shafts, said shafts being mounted at one end in knuckle-bearings, spring actuated means forcing the opposite

ends of the shafts toward the cone, cam-levers engaging said spring-actuated means, 15 a frame carrying the axes of said rollers, a rack on said frame, a gear-wheel engaging said rack, a segment engaging said gear-wheel, a single lever adapted to actuate said segment and to actuate the cam-levers to 20 force the shafts away from the cone and a pawl adapted to lock and unlock said gear-wheel in accordance with the movement of the lever.

NICOLAS GHERASSIMOFF.
